UNITED STATES PATENT OFFICE.

JAMES F. THAYER, OF PROVIDENCE, RHODE ISLAND.

FASTENER.

SPECIFICATION forming part of Letters Patent No. 324,895, dated August 25, 1885.

Application filed June 26, 1885. (No model.)

To all whom it may concern:

Be it known that I, JAMES F. THAYER, a citizen of the United States, and a resident of the city and county of Providence, and State 5 of Rhode Island, have invented an Improvement in Fasteners, of which the following description, in connection with the accompanying drawings, is a specification, like letters on the drawings representing like parts.

10 This invention is an improvement upon the fastener shown and described in my application for United States Letters Patent filed May 7, 1885, Serial No. 164,625.

As described in said application, that fastener consists in the main of two sides or halves, each having a penetrating prong or prongs, and joined by a top or connecting portion, which constitutes a part of the folded edge of the doubled stock from which the fastener is 15 cut. In the production of that form of fastener the legs or prongs of one side or half must necessarily be next to or touch the corresponding legs of the other half, because the die, in cutting the fastener from the doubled stock, forces the legs together, as readily understood, and it continues in such condition, except in so far as the spring in the metal tends to throw the legs apart. I have found that in thus striking the fastener from doubled stock 20 the die has a tendency, by reason of the force required, to flatten out or render thinner the legs of that half of the fastener which constituted a portion of the upper layer of the doubled stock, and also tends to bend or 25 slightly curve said legs to one side, so that their meeting edges at their extremities are carried to one side of the true line of said meeting edges. Under these conditions the die of the instrument employed to secure the 30 fasteners with contained buttons to fabric must not only be very exact with relation to the dividing ridge or wall between the two die-cavities, but the fasteners must also be placed in the instrument in the same relative 35 position—that is to say, if the first fastener be placed in the instrument with its slightly-concaved side farthest removed from the ends of the jaws of said instrument, to enable the prongs to be properly separated and clinched, 40 then the succeeding fasteners must be placed therein in the same manner; otherwise, by 45 reason of the slight curve in the legs of the

fastener, as stated before, the meeting edges will not come directly over the ridge in the die of the instrument, whereby the legs would 55 not be properly separated and clinched. To overcome these objections I provide my present fastener, which is cut from a single thickness of sheet metal, and is then bent at its middle to form equal sides or halves, each 60 having a penetrating prong or prongs, and adapted to permit the shank-eye of a button to be passed over a prong of one half and the corresponding prong of the other half, substantially as hereinafter more fully pointed 65 out.

Figure 1 is a plan of a strip of sheet metal from which a fastener-blank has been cut; Fig. 2, a plan of the blank; Fig. 3, a perspective view of my improved fastener; Fig. 70 4, a sectional view showing a button secured to fabric by means of my improved fastener; and Fig. 5, a perspective view, somewhat exaggerated and enlarged, of the fastener of 75 which my present invention is an improvement, to show clearly the slight bend in its legs as induced by the forming or cutting die.

The blank *a* is struck from the sheet-metal strip *A* by a suitable die, and is provided with penetrating-prongs *b* at each end, and is then 80 bent at its middle to provide equal sides or halves *c*, as shown.

The fastener, when completed, may have a *V* form or other suitable form in edge view, and the legs may be spread apart, as desired; 85 but in every form of my improved fastener the legs of one side must be sufficiently near the corresponding legs of the other side so as to permit the shank-eye of a button to be passed over a leg of one side and its corresponding leg of the other side, and thus enable the button-eye to encircle both legs, and thence to be passed on to the main portion, as 90 shown in Fig. 4. As shown, the legs of one half of the fastener are farthest removed from 95 the corresponding legs of the other half at their extremities.

With the fastener in the shape substantially as shown I am not only enabled to use a securing instrument of much less nicety and 100 accurateness of parts, but the fasteners may be indifferently placed in said instrument, while, important to add, the points of the prongs may be swaged in the act of bending

the blank at its middle in a bending machine. Further, the legs are of equal thickness throughout, and they may be clinched into the material toward each other, as shown in Fig. 4, instead of away from each other, as in the case of the fastener alluded to.

I am aware that it is not new to provide a fastener like that shown in the patent to C. H. Eggleston, dated February 12, 1884, No. 293,233, and I do not make claim to that or a similar fastener having a neck or connecting portion to receive a button, as described, or wherein the prongs are arranged so as to prevent the shank-eye of a button from being passed over a prong of each half or side of the fastener in the manner herein described.

I am also aware of United States Letters Patent granted to F. A. Smith, Jr., dated January 29, 1884, and numbered 292,516, and United States Letters Patent granted to Edward D. Steele, dated April 21, 1885, and numbered 316,304, and make no claim to anything therein shown or described.

What I claim is—
25 1. As an improved article of manufacture,

a fastener consisting, essentially, of two sides or halves, each provided with a penetrating prong or prongs, the prongs of one side being farthest removed from those of the other side at their extremities, as described.

2. A fastener consisting, essentially, of two sides or halves joined at one end, and having penetrating prongs at their other ends, the prongs of one half diverging from heel to point from those of the other half, substantially as set forth.

3. A fastener composed of a single strip of sheet metal, having penetrating prongs at each end, and a bend at its center to provide two diverging integral sides, the prongs of one side being apart from each other, as specified, and opposite corresponding prongs of the other side, substantially as described.

In testimony whereof I have signed my name to this specification in the presence of two subscribing witnesses.

JAMES F. THAYER.
